UNITED STATES PATENT OFFICE.

JOHN LUND, OF BETHLEHEM, PENNSYLVANIA, ASSIGNOR TO BETHLEHEM STEEL COMPANY, OF SOUTH BETHLEHEM, PENNSYLVANIA, A CORPORATION OF PENNSYLVANIA.

SEMI-AUTOMATIC BREECH MECHANISM FOR GUNS.

1,387,502.

Specification of Letters Patent. Patented Aug. 16, 1921.

Application filed May 3, 1916. Serial No. 95,124.

To all whom it may concern:

Be it known that I, JOHN LUND, a citizen of the United States, residing at Bethlehem, Northampton county, State of Pennsylvania, have invented certain new and useful Improvements in Semi-Automatic Breech Mechanism for Guns, of which the following is a specification.

This invention relates to a semi-automatic breech mechanism for guns.

The objects of the invention are to provide a semi-automatic breech mechanism for guns having an eccentric breech block; to operate such a mechanism by the recoil movement of the gun; to provide means to automatically close the block; to provide means to automatically eject the cartridge shell operated by the recoil of the gun; to provide means for storing up a portion of the energy of recoil to use the same to automatically close the block; and to embody these features in as simple a mechanism as possible.

These and other features of the invention, including certain details of construction and combination of parts, will be set forth in the following description and pointed out in the claims.

In the drawings:

Figure 1 is a top plan view of a portion of a gun equipped with the semi-automatic breech mechanism;

Fig. 2 is a side elevation of the same;

Fig. 3 is an end view showing the block in closed position;

Fig. 4 is an end view similar to Fig. 3 with the block removed;

Fig. 5 is a vertical longitudinal section through the block and adjacent parts, showing the block in closed position;

Fig. 6 is a section similar to Fig. 5 showing the block in open position.

The gun 10 is provided with a rotatable eccentric breech block 11, which is connected to the gun by means of a continuous thread 12 of the block, engaging a corresponding thread 13 cut in the breech recess of the gun.

These threads have a floating fit, the cylindrical surfaces 14, 15 forming the bearings

when the block is rotated. As clearly shown, the thread is shaped in cross section so as to take the rearward thrust of the block to the best advantage, that is, the two sides of a thread are not inclined equally, the side toward the rear of the gun being steeper than the other. The block is formed with an aperture 16 through which the cartridge is passed. This aperture is located eccentrically with respect to the axis of rotation of the block. When the block is open the aperture is opposite and in alignment with the bore of the gun, as shown in Fig. 6. When closed, the block is turned through 180° from its open position. The extent of this motion is controlled by a stop pin 17 carried by the block which travels in a substantially semi-circular groove 18 formed in the breech face 19. When the block is closed the pin is in the right end of the groove, as seen in Fig. 4. When open the pin is in the left end of the same, as the block turns 180° in a clock-wise direction, as seen in Fig. 3, to open. The block is provided with the usual firing case 20 which is operated by means of the firing lever 21. This firing mechanism may be of any suitable type. An operating handle 22 is attached to the block, so that the same may be operated manually if necessary or desirable.

A radial extension 23 on the block carries a roller 24 which coöperates with a cam surface 25 formed on a bracket 26 attached to the cradle 27 of the gun. As clearly shown in Figs. 1, 2 and 3, the bracket extends rearwardly from the gun and its inner surface is curved about the axis of rotation of the block. Obviously, the cam surface need not act on the block for the full 180° of its turning movement, as it may be designed of such shape that the block will be given sufficient momentum while turning through the first part of the 180° to fully open the same. A cam surface 28 reversely curved with respect to surface 25 is formed on bracket 26 for a purpose to be described later.

The block has a radial flange 29 at its rear end, formed with bevel gear teeth 30. As

clearly shown in Fig. 3, these teeth extend circumferentially for a little more than 180°, the remaining part of the flange having no teeth formed thereon. A stud 31 is attached 5 to the top of the breech, and a cable drum 32, formed with a bevel gear 33 is rotatably mounted on the stud. The gear 33 meshes with the teeth 30 on the block, so that rotation of the block revolves the gear 33. 10 Attached to the top of the breech by means of the screws 34 and tongue and groove connection 35 is a bracket 36 which carries a spring housing 37. The bracket 36 has a cable drum cover plate 38 hinged thereto as 15 at 39. This cover plate removably carries a bushing 40 which takes over the top of the stud 31, the bushing and thus the cover being held in place by a pin 41. The cover thus acts as a brace for the stud, and its 20 hinged connection facilitates rapid dismounting and assembling of the block. The spring housing 37 is arranged longitudinally of the gun so that its axis is substantially tangent to the cylindrical surface of the cable drum 25 32. A cable 42 or other flexible connection is attached at one end to the drum and seated in a helical groove 43 formed therein. The cable extends around the drum in the groove 43 and to the farther end of the spring housing, 30 where it is attached to a disk 44. Interposed between the disk 44 and the other end of the spring housing is a coiled compression spring 45. When the block is rotated by the recoil movement of the gun, through the 35 gears 30 and 33, drum 32 and cable 42, the spring 45 is compressed. Thus energy from the recoil of the gun is stored in the spring, and this energy is used to return the block to closed position. The spring and coöperating parts therefore constitute a motor. 40 It is obvious that other forms of motors such as fluid could be used, also other kinds of springs. Furthermore, the spring motor illustrated might be located or arranged in 45 various other positions and perform its function.

Directly over the bore of the gun, the breech recess is formed with a depression 46 of the shape illustrated in Fig. 4. A rectangular extractor shaft 47 having round bearings in the breech at 48 and 49 extends 50 across the depression. An extractor comprising arms 50 and the connecting piece 51 is mounted on the rectangular portion of the extractor shaft. The two arms 50 are adapted to be retracted into the recesses 52 formed in the breech. The arms are spaced apart so as to straddle a cartridge and catch against the rim of the same. A rectangular 55 portion of the piece 51 is cut away as at 53, and an extractor dog 54 is mounted in said cut away portion and on the rectangular shaft. This dog has a portion adapted to co-operate with a ramp or cam 55 formed in 60 the adjacent face of the breech block. The

cam is designed so as to impart to the extractor a slow and powerful movement at first, followed by a rapid movement, which finally ejects the cartridge case, clear of the gun. The extractor dog has an arm 56 70 against which a spring 57 acts to normally retract the dog within the depression 46.

The extractor shaft also carries non-rotatively a block locking arm 58, which can be retracted into a recess 59 formed in the 75 breech. This arm is provided with a lip 60 which is adapted to catch in a correspondingly shaped recess 61 in the block. The arm and recess form a block lock to hold the block in open position. The lock may be released by operating the handle 62 attached to the extractor shaft, or may be actuated to release the block automatically when a shell is inserted, the shell acting against the extractor arms to rotate the extractor shaft and 80 release the lock.

The operation of the mechanism is as follows: The recoil of the gun causes the roller 24 on the breech block to travel along the cam 25, thus rotating the block to open position. While rotating, the ramp or cam 55 acts on the extractor to eject the shell and to operate the block lock, the action of the cam being supplemented by the spring 57, so that the last portion of the movement of the 95 extractor and block lock is due to the said spring. By means of the bevel gears and the cable the spring is compressed, thus storing up some of the energy of recoil, to be used to close the block. When a shell is inserted, the block lock is automatically released, and the spring motor operates to close the block. If, for any reason, the block does not rotate to its open position or is not locked open, and returns to closed position before the gun 100 has returned to battery, then the roller 24 will ride on the cam surface 28, thus permitting the gun to return to battery. If the cam 26 terminated at the low point, and the bracket were formed with a flat end face, 105 under the above conditions, the roller would probably strike the flat end face, either breaking a part, or preventing the gun from returning to battery.

Having thus described the invention, what 110 is claimed and desired to be secured by Letters Patent is:

1. A semi-automatic breech mechanism for guns comprising a breech block mounted for rotation about an axis parallel to and offset 115 from the axis of the gun barrel and moving with the barrel at all times, means for rotating said block to open the same operated by and during the recoil of the gun, a spring connected to said breech block and tending 120 to close the same, and a releasable lock for holding the block in open position.

2. In a semi-automatic breech mechanism for guns having a breech block mounted for rotation about an axis parallel to and offset 125

from the axis of the gun barrel, a motor acting to close said block, and means including a block rotating element for storing energy in said motor, operated by and during the

5 recoil of the gun.

3. In a semi-automatic breech mechanism for guns having a rotatably mounted eccentric breech block, a cam carried by the cradle of the gun, a roller on the block coöperating 10 with the cam whereby the block will be rotated to open position on recoil of the gun, a spring connected to the block and tending to close the same, and releasable means for holding the block open.

15 4. In combination with a gun, a semi-automatic breech mechanism including a breech block mounted to rotate about an axis parallel to but offset from the axis of the gun barrel, means for rotating the block to open 20 the same during the recoil of the gun, a cartridge case ejector and a cam on the block for operating said ejector.

5. In combination with a gun, a semi-automatic breech mechanism including a breech 25 block mounted to rotate about an axis parallel to but offset from the axis of the gun barrel, means for rotating the block to open the same during the recoil of the gun, a cartridge case ejector and a cam formed on the 30 inner end of the block for operating said ejector.

6. In combination with a gun, a semi-automatic breech mechanism including a breech block mounted to rotate about an axis parallel to but offset from the axis of the gun 35 barrel, means for rotating the block to open the same during the recoil of the gun, a cartridge case ejector mounted between the inner end of the block and the gun barrel and 40 a cam formed on said inner end for operating said ejector.

7. In combination with a gun, a semi-automatic breech mechanism including a breech block moving with the gun barrel at all times 45 and mounted for rotation about an axis parallel to and offset from the axis of the gun barrel, means for automatically opening said block during the recoil of the gun, releasable means for holding the block in open position, and means for automatically closing 50 said block when it is released.

8. In combination with a gun having a breech recess the axis of which is offset relative to the axis of the gun barrel, a breech 55 block rotatively mounted in said recess, means for automatically rotating said block to open the same during the recoil of the gun, and releasable means arranged between the bottom of the recess and the inner end of the 60 block for holding the block in open position.

9. In combination with a gun, a semi-automatic breech mechanism including a breech block mounted for rotation about an axis parallel to and offset from the axis of the gun 65 barrel, means for rotating said block to open

the same operated by the recoil of the gun, a motor acting to close said block, and means for storing energy in said motor operated by the opening rotation of said block.

10. In combination with a gun, a semi-automatic breech mechanism including a rotatably mounted breech block, means operated by the recoil of the gun for rotating said block to open the breech, a motor acting to close said block, and means for storing energy in said motor operated by the block and during its rotation in opening. 70

11. In combination with a gun, a semi-automatic breech mechanism including a breech block rotatable on an axis parallel to the axis of the gun, means operated by the recoil of the gun for rotating said block to open the breech, a motor acting to close said block and means for storing energy in said motor operated by the block and during its 85 opening movement.

12. A semi-automatic breech mechanism for guns comprising a breech block mounted to move to open and close the breech, means to open the block, a rotatably mounted drum, 90 a spring, a connector secured to the spring and adapted to be wound on the drum, means actuated by the opening movement of the block to rotate said drum and place the spring under strain, and a releasable device 95 to hold the block open.

13. A semi-automatic breech mechanism for guns comprising a breech block mounted to move to open and close the breech, means to open the block, a rotatably mounted drum, 100 a spring associated with said drum, gearing connecting the block and drum whereby the drum is rotated by the opening movement of the block and the spring placed under strain, and a releasable device to hold the block 105 open.

14. The combination with a gun having a circular breech recess the axis of which is offset from the gun axis, a breech block rotatably mounted in said recess and formed 110 with a cartridge aperture, and means to rotate said block to bring the aperture into register with the bore of the gun operated by and during the recoil of the gun.

15. The combination with a gun having 115 a circular breech recess the axis of which is offset from the gun axis, a breech block rotatably mounted in said recess and formed with a cartridge aperture, and means to rotate said block to bring the aperture into 120 register with the bore of the gun operated by the recoil of the gun, said means including a cam member on the cradle.

16. The combination with a gun having a circular breech recess the axis of which is offset from the gun axis, a breech block rotatably mounted in said recess and formed with a cartridge aperture, means to rotate said block to bring the aperture into register 125 with the bore of the gun operated by and 130

during the recoil of the gun, a spring tending to turn said block to close the bore, and a releasable device to hold the block open.

17. The combination with a gun having a circular breech recess the axis of which is offset from the gun axis, a breech block rotatably mounted in said recess and formed with a cartridge aperture, means to rotate

said block to bring the aperture into register with the bore of the gun operated by and 10 during the recoil of the gun, and means operated by the said rotation of the block to eject the cartridge.

In testimony whereof I affix my signature.

JOHN LUND.
